(57) **CLAIM**

The ornamental design for a novel manual slicing device, substantially as shown.

DESCRIPTION

FIG. 1 is a perspective view of the slicer constructed in accordance with the present invention;

FIG. 2 is a top plan view of the slicer of FIG. 1;

FIG. 3 is a right side elevation of the slicer of FIG. 1;

FIG. 4 is a bottom plan view of the slicer of FIG. 1;

FIG. 5 is a front elevation of the slicer of FIG. 1;

FIG. 6 is a rear elevation of the slicer of FIG. 1; and,

FIG. 7 is a left side elevation of the slicer of FIG. 1.
